United States Patent Office

Des. 198,336
Patented June 2, 1964

198,336

TOLL COLLECTION MACHINE OR SIMILAR ARTICLE

John A. Bellinger, 3041 Krollwood Lane, Glenview, Ill.,
and Troy J. Lowe, 5731 Higgins Road, Chicago, Ill.

Filed Aug. 5, 1963, Ser. No. 76,092

Term of patent 14 years

(Cl. D52—4)

Fig. 1

Fig. 2

Fig. 3

Fig. 4

FIG. 1 is a perspective view of a toll collection machine or similar article showing our new design.

FIG. 2 is a side elevational view thereof, showing the side which is hidden in FIG. 1.

FIG. 3 is a rear elevational view of the toll collection machine or similar article.

FIG. 4 is a top plan view thereof.

We claim:

The ornamental design for a toll collection machine or similar article, as shown and described.
